UNITED STATES PATENT OFFICE

115,303

DESIGN FOR A MERCHANTISE DISPLAY STAND

James F. Urbanek, Elmwood Park, Ill.

Application October 13, 1938, Serial No. 80,427

Term of patent 7 years

To all whom it may concern:

Be it known that I, James F. Urbanek, a citizen of the United States, residing at Elmwood Park, in the county of Cook and State of Illinois, have invented a new, original, and ornamental Design for a Merchandise Display Stand, of which the following is a specification, reference being had to the accompanying drawing, forming a part thereof.

I claim:

The ornamental design for a merchandise display stand, substantially as shown.

JAMES F. URBANEK.
